UNITED STATES PATENT OFFICE

FRANK L. BRYANT, OF CHICAGO, ILLINOIS, ASSIGNOR, BY MESNE ASSIGNMENTS, TO
CELLUFOAM CORPORATION, OF CHICAGO, ILLINOIS, A CORPORATION OF DELAWARE

AGITATOR

Application filed May 16, 1930. Serial No. 452,901.

The agitator of this invention is designed primarily for the purpose of agitating a mixture of cellulose fibres and chemical agents adapted to distend the mass by the formation of minute cells or bubbles, as set forth in Patent No. 1,740,280, issued December 17, 1929, relating to the product in question. However, the present agitating apparatus is adapted for other uses in which a thorough mixing and agitation of the ingredients is required, and in which it is desirable to secure such results without unduly disintegrating the fibres or other materials subjected to agitation.

The agitator is in the form of one or more propellers having blades disposed in a peculiar and distinctive manner, and in such a way as to impart vertical movement to the mass in conjunction with an outward or centrifugal action combined with a surging effect which is occasioned by the decentered position of the agitator within the tank or receptacle.

Further objects and details will appear from a description of the invention in conjunction with the accompanying drawings, wherein,

Figure 1 is a sectional elevation of a tank showing the agitator of the present invention;

Fig. 2 is a plan view of one of the agitating propellers; and

Figs. 3 and 4 are sectional elevations taken respectively on lines 3—3 and 4—4 of Fig. 2.

The agitator of the present invention is housed within a cylindrical tank 10, and the propellers 11, of which two are shown, are mounted upon a vertical shaft 12 which is decentered with respect to the axis of the tank, being nearer to one side wall than to the other. As shown, the shaft 12 is operated from a motor 13 which drives a pulley 14 connected with the shaft.

Each of the propellers in the form shown comprises a hub 15 which is fixedly mounted upon the shaft by the use of a set screw 16. As shown, the inner portion 17 of the propeller adjacent the hub is plane or flat and of square formation, and from each of the four edges springs a propeller blade 18 in

the case of a four-bladed propeller, although the number of blades might be increased or diminished, in which case obviously the configuration of the flat center portion of the propeller would be varied accordingly to present a triangular or polygonal figure, having a number of sides corresponding to the number of blades.

Each of the blades is of substantially semi-heart-shaped formation, and stands in obliquely upwardly extending relation to the flat center portion 17. The outer edge 19 of the blade extends outwardly from one of the corners of the flat center portion 17 on a curve of progressively diminishing radius, the rear or tip end of the blade 20 being extended behind the proximate corner of the center portion 17, and each being recurved inwardly and forwardly until it terminates at or near said last mentioned corner.

The tip 20, which is of substantially semi-circular formation, is turned or flexed downwardly, as best shown in Fig. 4, so that, as the propeller of Fig. 2 revolves in a counter-clockwise direction, the rear tip end of the blade will impart a downward thrust to the liquid mixture being subjected to agitation.

At the same time, the upward oblique relation of the body of the blade as a whole will subject the mixture to an outward or centrifugal thrust, while the leading curved edge of the blade is given a proper curvature at all points to cause the particles of liquid under agitation, which impinge against said leading edge, to be deflected outwardly and away from the hub, which is highly desirable where the propeller is used in the agitation of fibrous mixtures held in suspension in a liquid, which if thrust inwardly by the action of the propeller might tend to clog around the shaft.

With the propeller or propellers of the character described mounted upon a shaft standing in decentered relation to a cylindrical tank or tub, the action of the propellers, when rotated in a counter-clockwise direction, will be to cause the mixture of liquid and solid materials to be driven outwardly or in a radial direction, and at the same time to be driven downwardly by the down-

turning of the tips of the blades, and this outward and downward movement will be compounded with a rotating movement around an agitator shaft which is decentered with respect to the tank, so that the material, in its circuit around the tank, will in turn 5 recede away from the agitator, and then be driven inwardly toward the agitator, which produces a surging and vortical action which is very effective in thoroughly commingling the particles in the mixture, without, however, subjecting the fibres or other materials to disintegrating action. At the same time, 10 the action is one which is effective in the formation of bubbles or minute cells which distended the mass in the manner fully described in Patent No. 1,740,280.

The invention is one which, although designed primarily to deal with the materials 20 specified in said patent, can, nevertheless, be used to advantage under other circumstances in which an effective agitating action of the character specified is desired.

Although the invention has been described 25 with full detail, it is subject to modification without departing from the principles involved. Thus, although the tank or receptacle 10 as shown and described is truly cylindrical, it obviously might have the bulging 30 formation of a vat or barrel, so that in the use of the term cylindrical in the specification and claims, it will be understood that this term is intended to cover receptacles which depart more or less from truly cylindrical 35 formation. Furthermore, although for certain purposes it is desirable to locate the agitator off center in the tank or receptacle, it is not the intention, unless so indicated in the 40 claims, to limit the invention in this respect, since for certain purposes a centrally located agitator will subserve the agitating function intended.

I claim:

1. In agitating apparatus of the character 45 described, the combination of a receptacle for mixtures to be subjected to agitation, a shaft extending into said receptacle, and a propeller on said shaft consisting of a flat center portion and a plurality of blades extending radially upwardly in oblique relation 50 to said center portion and outwardly therefrom, the tip of each blade extending backward beyond the line of attachment thereof to said center portion, and the tip 55 at the end of the circumferential extent of the blade being downturned and having its edges recurved forwardly toward said center portion.

2. In agitating apparatus of the character 60 described, the combination of a receptacle for mixtures to be subjected to agitation, a shaft extending into said receptacle, and a propeller on said shaft consisting of a flat center portion of polygonal formation having 65 straight intersecting edges, and a blade

outwardly extending from each edge and standing in obliquely upwardly extending relation thereto, and having the tip of the blade extended rearwardly beyond the side of the center portion to which the blade is 70 attached.

3. In agitating apparatus of the character described, the combination of a receptacle for mixtures to be subjected to agitation, a shaft extending into said receptacle, and a propeller on said shaft consisting of a flat center portion of polygonal formation having straight intersecting edges, and a blade outwardly extending from each edge and standing in obliquely upwardly extending relation thereto, and having the tip of the blade extended rearwardly beyond the side of the center portion to which the blade is attached, each blade tip being downwardly curved and having its edge recurved and extending forwardly to substantially the rear end of the side to which the blade is attached. 80

4. In agitating apparatus of the character described, the combination of a cylindrical receptacle for mixtures to be subjected to agitation, a shaft extending vertically into said cylindrical receptacle and in decentered relation thereto, and a propeller on said shaft, consisting of a flat center portion of polygonal formation having straight intersecting edges, and a blade outwardly extending from each edge and standing in obliquely upwardly extending relation thereto, and having the tip of the blade extended rearwardly beyond the side of the center portion to which the blade is attached. 90

5. In agitating apparatus of the character described, the combination of a cylindrical receptacle for mixtures to be subjected to agitation, a shaft extending vertically into said cylindrical receptacle and in decentered relation thereto, and a propeller on said shaft, consisting of a flat center portion of polygonal formation having straight intersecting edges, and a blade outwardly extending from each edge and standing in obliquely upwardly extending relation thereto, and having the tip of the blade extended rearwardly beyond the side of the center portion to which the blade is attached. 100

In witness that I claim the foregoing I have hereunto subscribed my name this 13th day of May, 1930.

FRANK L. BRYANT.
